BALLET BARRE

Nicholas I. Nahumck, 271 S. Van Pelt St.,
Philadelphia, Pa. 19103

Filed Apr. 17, 1968, Ser. No. 11,486

Term of patent 14 years

Int. Cl. D21—03

U.S. Cl. D25—1

Fig. 1

Fig. 2

The broken line showing of a dance figure is for illustrative purposes only.

I claim:

The ornamented design for ballet barre, as shown and described.
